UNITED STATES PATENT OFFICE.

EDWARD W. BASSETT, OF TOLEDO, OHIO, ASSIGNOR TO THE CELMA COMPANY, OF TOLEDO, OHIO, A CORPORATION OF OHIO.

VANITY CASE.

Application filed July 1, 1925. Serial No. 40,896.

To all whom it may concern:

Be it known that I, EDWARD W. BASSETT, a citizen of the United States, and a resident of Toledo, in the county of Lucas and State of Ohio, have invented a new and useful 5 Vanity Case, which invention is fully set forth in the following specification.

This invention relates to toilet articles, and, particularly, to vanity cases for containing powder in loose form and other articles, such for instance, as a powder puff.

The object of my invention is to improve on the vanity case covered by United States Letters Patent No. 1,451,955, dated April 15 17, 1923, whereby to enhance the practicability and commercial value thereof.

One embodiment of the invention is illustrated in the accompanying drawing.

Figure 1 is a top view of a case embodying the invention with the cover open. Fig. 2 is an enlarged fragmentary section thereof on the line 2—2 in Fig. 1. Fig. 3 is an enlarged fragmentary plan of the perforated diaphragm member of the case, and Fig. 4 is a fragmentary sectional view thereof.

Referring to the drawings, 1 designates the body or bottom portion and 2 the cover of a vanity case embodying the invention; which members may be hinged together and are preferably, though not necessarily, circular in form. The body portion 1 is provided therein with a removable diaphragm 3 of any suitably fairly stiff material of a flexible nature such for instance, as celluloid, tin, cardboard or the like, and this diaphragm is adapted to fit into the body member and is spaced from its bottom by any suitable edge spacing means to form a false bottom therefor. In the present instance, such spacing means comprises a ring 4 of felt, card board, or other suitable material which is glued or otherwise suitably fixed in the bottom of the case body around the interior edge portion thereof to form a ledge or raised portion within such marginal edge portion of the case. A similar ring member 5 preferably of felt-like material, is secured to the under marginal edge portion of the diaphragm 3 in position to seat down on the ring or ledge 4 in the case bottom, the rings 4 and 5, being preferably of a yielding material, readily accommodate themselves to each other, and form a fairly tight joint which tends to prevent the escape of powder

between such rings and around the edge of the diaphragm 3.

The diaphragm 3, which is of disc form when used in connection with a circular form of case, is supported by the members 4 and 5 or other suitable spacing means above the bottom of the case body and cooperates therewith to form a chamber 6 in the bottom portion of the case for containing a quantity of powder, and also forms the bottom of an upper chamber 7. The diaphragm being of a flexible nature is adapted to have its central portion pressed down into the portion 6 and is provided in such central or depressible portion with one or more perforations 8 so that when depressed into engagement with the powder in the chamber 6 the air which rushes out from such chamber through the perforations during the compressing action carries with it a greater or less quantity of powder which gathers on the top of the diaphragm 3 in segregated relation to the powder in the chamber 6 and in position to be gathered up by the powder puff. It is found in practice that it is not necessary to completely compress the diaphragm 3 to eject powder from the chamber 6 on to the top of the diaphragm, but that a few light taps of a finger on the diaphragm will cause a sufficient agitation of air within the chamber to eject a small quantity of powder therefrom.

The construction so far described is disclosed in said former Patent No. 1,451,955 and no claim is made herein for the same.

It is found in the use of this vanity case that while the ring members 4 and 5 are supposed to seat closely one upon the other and prevent the escape of powder therebetween and around the edge of the diaphragm from the case 6 that such escape takes place and that this is more or less objectionable. To obviate this feature a coarse form of stitching 9 is provided over and around the marginal edge portion of the diaphragm 3 through the ring member 5 so that the edge of the diaphragm is entirely enveloped by such stitching. This forms an edge binding for the diaphragm and not only serves to secure the ring member 5 to the diaphragm but also provides an edge gasket or packing on the diaphragm, which, when the diaphragm is inserted in the body 1 of the case, coats closely with the wall of the case to prevent the escape of powder from

- the chamber 6 around the diaphragm edge. This edge gasket also serves to yieldingly retain the diaphragm in position within the case. The stitch 9 employed is, preferably, 5 of the open type with cross or connecting loops provided both at its inner edge 10 and at its outer peripheral edge 11, the latter loops forming a packing or gasket portion around a periphery of the diaphragm 10 for engagement with the wall of the container in which fitted. While the ring member 5 has been described as being glued to the diaphragm it is apparent that it may be secured thereto alone by the stitching. 15 The provision of the binding around the edge of the diaphragm is found to very materially improve the action and use of the device, in that it serves to prevent the escape of powder from the chamber 6 around 20 the edge of the diaphragm and also to retain the diaphragm closely seated on the ring member 4.

I wish it understood that my invention is not limited to any specific construction, arrangement or form of the parts, as it is capable of numerous modifications and changes without departing from the spirit of the claims.

Having thus described my invention, what 30 I claim as new and desire to secure by Letters Patent is:

1. In a vanity case, a flexible diaphragm 35 removably mounted therein and cooperating with the case bottom to form a powder receiving chamber, the diaphragm having a binding around its marginal portion and embracing its edge to form a packing for engagement with the side wall of the case to provide a close joint therebetween.
2. In a vanity case, a flexible diaphragm 40 removably mounted therein and cooperating with the case bottom to form a powder receiving chamber, the diaphragm having a stitching around its marginal portion and 45 embracing its edge to form a packing for engagement with the side wall of the casing to form a close joint therebetween.
3. In a vanity case, a flexible diaphragm

removable therefrom and having centrally disposed perforations, means spacing the 50 marginal edge portion of the diaphragm from the bottom of the container to form a powder receiving chamber between the diaphragm and case bottom, said diaphragm having a binding around its marginal edge 55 portion and enveloping its peripheral edge to form a gasket for engagement with the side wall of the case to form a close joint between the diaphragm edge and the case.

4. In combination, a vanity case, a flexible 60 diaphragm removably mounted in the case and having centrally disposed perforations, a member secured marginally to the under side of the diaphragm and extending entirely around the same, a stitching through 65 the diaphragm and member and forming a peripheral binding entirely around the diaphragm for coaction with the side wall of the case to form a close joint between the diaphragm and such wall, said marginal 70 member serving to space the diaphragm from the bottom of the case to form a powder chamber therebetween.

5. In combination with the body portion of a vanity case of a centrally perforated 75 diaphragm of a flexible nature removably mounted in the case body in spaced relation to its bottom to form a powder chamber therebetween, a marginal member of felt-like material secured to the underside of the 80 diaphragm entirely around the same and a stitching through the diaphragm and member entirely around the marginal edge portion of the diaphragm, said stitching being of loose form and having cross loops at its inner edge and cross loops at its outer edge with the latter cross loops disposed around the peripheral edge of the diaphragm and forming a gasket portion for closely engaging the side wall of the case body and providing a close joint between it and the diaphragm edge.

In testimony whereof I have hereunto signed my name to this specification.

EDWARD W. BASSETT.
